UNITED STATES PATENT OFFICE.

GEORGE G. PROBERT, OF NATIONAL MILITARY HOME, KANSAS.

ROTARY ENGINE.

SPECIFICATION forming part of Letters Patent No. 792,614, dated June 20, 1905.

Application filed May 18, 1904. Serial No. 208,635.

To all whom it may concern:

Be it known that I, GEORGE G. PROBERT, a citizen of the United States, residing at National Military Home, in the county of Leavenworth and State of Kansas, have invented certain new and useful Improvements in Rotary Engines, of which the following is a specification.

My invention relates to improvements in rotary engines propelled by steam, water, gas, or other fluid; and one of my objects is to gain the full efficiency of the fluid-pressure by applying it to the piston of the engine in the most direct manner instead of permitting it to lose its force by pursuing a tortuous path before and when acting on said piston.

A further object is to provide simple means for reversing the motion of the piston.

The essential features of the invention consist in two members, one of which is stationary and has communicating inlet, by-pass, and exhaust ports, while the other acts as a rotary piston and has a series of concentrically - arranged grooves communicating with the by-pass ports, said grooves having transverse heads against which the fluid impinges when propelling the piston.

Another feature of the invention resides in the peculiar manner in which friction is reduced to a minimum between the stationary member and the rotating piston.

Other features of the invention will hereinafter appear, and in order that it may be fully understood reference will now be made to the accompanying drawings, in which—

Figure 1 represents a horizontal section of the invention, taken on line I I of Fig. 3. Fig. 2 is a plan view of the stationary disk forming part of the invention. Fig. 3 is a transverse section of the engine, taken on line III III of Fig. 1. Fig. 4 is an irregular section of the reversing-valve and one of the by-passes, taken on line IV IV of Fig. 1. Fig. 5 is an irregular broken transverse section of the stationary disk, taken on line V V of Fig. 1, showing one of the by-pass ports communicating with the exhaust-port. Fig. 6 is a detail perspective view of the reversing-valve forming part of the invention. Fig. 7 is a

vertical transverse section of a modification of the engine, wherein the fluid acts on both sides, and the periphery of the piston, taken on line VII VII of Fig. 8. Fig. 8 is a broken irregular section of the same, taken on line VIII VIII of Fig. 7, showing the by-passes through which communication is established between the groove in the periphery of the piston and the side grooves thereof.

The stationary member of the engine is preferably arranged in the form of a disk 1, provided at its top and bottom portions with centrally-disposed bosses 2 and 3 and at one side with a peripheral boss 4, through which latter a tapering valve-seat 5 extends to within a short distance of the center of the disk and communicates with an inlet-port 6, extending to the outer end of boss 3, which latter is threaded for the reception of the threaded end of a supply-pipe 7, leading from a boiler or other source from which fluid under pressure is conducted.

8 8^a 8^b 8^c designate a series of by-passes communicating at their opposite ends with one side of valve-seat 5 and the upper surface of disk 1. 9 9^a 9^b 9^c designate a series of similar by-passes communicating with the opposite side of the valve-seat 5 and the upper side of the disk. The by-passes gradually increase in area toward the periphery of the disk for a purpose hereinafter described, and the two larger ones communicate with a centrally-disposed exhaust-port 10, leading from the lower side of the disk, as shown in Figs. 3 and 5.

85 The passage of fluid through the by-passes is controlled by the reversing-valve 11, comprising a tapering plug 12, which snugly fits within valve-seat 5, a conical-formed portion 13 for closing the outer end of the valve-seat, 90 a triangular portion 14, connecting the outer end of the plug to the conical-formed portion 14, and a handle 15, secured to the latter for operating the plug. Plug 12 is provided at its opposite sides with grooves 16 17, inclined in opposite directions, as shown in Figs. 2 and 4, and gradually increasing in width toward the outer end of the plug in order to correspond with the by-passes.

95 Disk 1 is provided with peripheral lugs 18 100

for the reception of screws or bolts whereby it is secured to a suitable foundation when the engine is in use.

The rotary member of the engine preferably consists of a disk or piston 19 of the same diameter as the disk 1, upon which latter it is loosely mounted, the piston being provided with a centrally-disposed counter-bore 20 for the reception of boss 2. The lower side of the piston bears against the upper side of the disk and is provided with a series of concentric grooves 21 21^a 21^b 21^c, which register with the by-pass ports and, like the latter, gradually increase in size toward the periphery of the piston. Each groove is closed by a transverse head 22 22^a 22^b 22^c, arranged on different sides of the axis of the piston, as shown in Fig. 1, in order to balance the latter when the fluid impinges against said heads and also prevent the latter from simultaneously reaching the practically dead point between the adjacent sides of the by-pass ports, where the fluid exerts but slight pressure upon the transverse heads, owing to the fact that the greater portion of said fluid passes through the by-passes at said point.

Motion is transmitted to the load from the piston through a stub-shaft 23, extending upwardly from the latter.

In practice the piston is rotated from left to right by turning valve 11 to the position shown in Fig. 1. This permits the fluid entering port 6 to flow through the innermost groove 16, thence through by-pass 8, and into groove 21 of the piston, which latter is rotated by impact of the fluid against transverse head 22. After said head passes port 9 the greater portion of the fluid flows downwardly therethrough into the communicating groove 17, thence through by-pass 8^a into groove 21^a, impinging against head 22^a until the latter passes by-pass 9^a, where the larger portion of the fluid flows down into the communicating groove 17, thence out through by-pass 8^b into groove 21^b, impinges against head 22^b until the same passes by-pass 9^b, where the larger portion of the fluid flows into groove 21^c through by-pass 9^b, thence through communicating groove 17 and by-pass 8^c, from which latter it flows through by-pass 9^c into the communicating groove 17 and escapes through the exhaust-port 10 as head 22^c passes by-pass 9^c. The motion of the piston can be readily reversed by turning the valve 11 a one-half revolution, which brings groove 16 in communication with the by-passes.

From the above description it will be understood that the fluid pursues substantially a continuous course uninterrupted by sharp curves from the time of entering the grooves of the cylinder until it leaves the same, and as said grooves gradually increase in cross-section the fluid will not be retarded to the

same extent by friction as it progresses toward the exhaust-port, and consequently will exert about equal pressure on head 22^c as on head 22.

It is obvious that the fluid in the grooves of the piston will exert an upward pressure on the latter and tend to raise it from the disk; but in practice this tendency is counteracted by the load, which is arranged to exert a downward pressure through the instrumentality of worm or other gearing. (Not shown.) Means for lubricating the adjacent sides of the piston and the disk are unnecessary, as the lifting action of the fluid on the piston will prevent the latter from bearing too heavily on the disk, and more or less moisture from the fluid will be forced by the latter between the contacting sides, thereby reducing the friction created by same to a minimum.

While I have shown the engine arranged in a horizontal position, it is obvious that it will operate equally as well in any other position.

In the modification shown in Figs. 7 and 8 piston 19^a is inclosed in a casing 1^a and provided on one side with grooves 21 to 21^c, a peripheral groove 21^d, and a groove 21^e on its opposite side, which communicates with an exhaust-port 10^a, leading from one side of the casing. Groove 21 communicates with an inlet-port 6^a, while groove 21^c communicates with peripheral groove 21^d through a by-pass 9^d in the lower portion of the casing. Communication is established between the peripheral groove 21^d and the exhaust-port 10^a through a by-pass 9^e, arranged in the casing.

In the modification just described the reversing-valve is omitted, as it is intended that the piston shall travel in but one direction. The construction shown in Figs. 1 and 2 may also be modified by omitting the reversing-valve, in which case but one set of by-passes will be employed, having ports in the top of the disk arranged like those shown in Fig. 2.

While I have shown and described the inlet-port communicating with the axis of the disk and the exhaust-port located near the periphery thereof, the position of said ports may of course be reversed, in which case grooves — will be the larger of the series and groove — the smaller, while the by-passes will be arranged to correspond therewith.

Having thus described my invention, what I claim, and desire to secure by Letters Patent, is—

1. A rotary engine having a stationary member provided with by-passes and inlet and exhaust ports communicating with a number of the by-passes, a rotary member having grooves for establishing communication between the by-passes, and heads extending across the grooves.

2. A rotary engine having a stationary member provided with by-passes and inlet and exhaust ports communicating with a number of the by-passes, a rotary member having concentric grooves for establishing communication between the by-passes, and heads extending across the grooves. 35
3. A rotary engine having a stationary member provided with obliquely-arranged by-passes and inlet and exhaust ports communicating with a number of the by-passes, a rotary member having grooves for establishing communication between the by-passes, and heads extending across the grooves. 40
- 15 4. A rotary engine having a stationary member provided with by-passes and inlet and exhaust ports, a rotary member having concentric grooves for establishing communication between the by-passes, said by-passes and concentric grooves gradually increasing in cross-section as they approach the exhaust-port, and heads extending across the grooves. 45
- 20 5. A rotary engine having a stationary disk provided at one side with inlet and exhaust ports and at its opposite side with a series of by-passes one of which communicates with the inlet-port while another communicates with the exhaust-port, a piston rotatably mounted on the side of the disk adjacent to the by-passes provided with concentric grooves for establishing communication between the latter, and heads extending across the grooves. 50
- 25 6. A rotary engine having a stationary member provided with a valve-seat, by-passes communicating therewith and inlet and exhaust ports also communicating with the valve-seat, a reversing-valve arranged in the valve-seat for controlling the direction of the fluid through the by-passes and establishing communication between two of the latter and the inlet and the exhaust ports, a rotary member mounted on the stationary member and provided with grooves for establishing communication between the by-passes, and heads extending across the grooves. 55
- 30 7. A rotary engine having a stationary member provided with a valve-seat, by-passes communicating therewith and inlet and exhaust ports also communicating with the valve-seat, a reversing-valve arranged in the valve-seat provided at its opposite sides with oblique grooves extending in opposite directions for controlling the direction of the fluid through the by-passes and establishing communication between two of the latter and the inlet and the exhaust ports, a rotary member mounted on the stationary member and provided with grooves for establishing communication between the by-passes, and heads extending across the grooves. 60

In testimony whereof I affix my signature in the presence of two witnesses.
